UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,025, dated May 27, 1884.

Application filed March 27, 1884. Term of patent 31 years.

To all whom it may concern:

Be it known that I, SARAH JANE SHIELS, of the city, county, and State of New York, have invented and produced a new and original Design for a Pattern of a Lady's Costume, (numbered 9,169;) and I do hereby declare that the engraved prints accompanying this specification convey to any one accustomed to using paper patterns a clear understanding of how a garment made up by the pattern will appear.

The design shows a round walking-skirt and an overdress. The overdress displays short-pointed center fronts, with buttons all the way down, deeply-pointed side fronts that exhibit 15 clustered shirrings at the shoulders and waistline and draping plaits in their back edges, a

closely-fitted pointed body-back that displays a deep double-pointed depending drapery exhibiting a gathering in its upper edge and draping plaits at its center and front edges, 20 coat-sleeves exhibiting rolling cuffs flaring at their back edges, and a standing collar.

What I claim as my invention, and desire to secure by Letters Patent, is—

The design for a lady's costume, as shown in 25 the engraved prints accompanying this specification.

SARAH JANE SHIELS.
